UNITED STATES PATENT OFFICE.

CHARLES W. HEASLEY, OF PITTSBURGH, PENNSYLVANIA.

CUFF LINK.

Application filed December 13, 1927. Serial No. 239,680.

This invention relates to cuff-links and more particularly to expandible, self-adjusting cuff-links.

One of the main objects of this invention is 5 to provide a cuff-link exerting a constant yielding pressure on both flaps of a sleeve-cuff, whereby said cuff may be closed or expanded without requiring any adjustment or manipulation on the cuff-link. Another object of this invention is to provide in the flexible member connecting both cuff-buttons means whereby said buttons may be readily connected or disconnected to facilitate the 10 insertion of the individual cuff-buttons in their respective button-holes, or the extraction therefrom. Additional features and advantages of this invention will appear from the following description considered in connection with the accompanying drawing 15 forming a part of this application, and in which:

Fig. 1 is a sectional view of one button of the cuff-link.

Fig. 2 is an elevation, partly in section, of 20 the companion button to Fig. 1.

Fig. 3 is a fragmentary sectional view showing both buttons of the cuff-link connected together.

Figs. 4 and 5 are enlarged detail views 25 showing the preferred means for connecting the flexible members of both buttons together.

Fig. 6 is a front elevation of the connecting element shown in Fig. 4.

Figs. 7 and 8 show another method of 30 readily connecting the flexible members of a cuff-link.

Fig. 9 represents a third method of connecting said flexible member.

Fig. 10 is an end elevation of the left hand 35 connecting element shown in Fig. 9.

Fig. 11 is a front elevation of the right hand connecting element of Fig. 9, with the catch-member removed.

Fig. 12 is a perspective view of the catch 40 member used in Fig. 9.

This application is especially intended to 45 cover an important improvement and addition to an expandible cuff-link invented by me and which forms the subject matter of 50 Patent Number 1,645,907, dated October 18, 1927.

The disadvantage of this last named cuff-link, as well as many other patented cuff-links of this type, lies in the fact that, in order to 55 fasten the connected cuff-links to sleeve-cuffs, the rather voluminous outside buttons of said

links must be passed through the button-holes of the cuffs. These holes being sometimes too small to accommodate said buttons, it, therefore, becomes necessary to enlarge them 60 to suit the cuff-links.

To overcome this inconvenience and enable the wearing of cuff-links having outside buttons of any desirable shape and dimensions, regardless of the size of the button-holes, I 65 prefer to use the improved construction detailed in Figs. 1 to 6. As shown therein, the general design of this cuff-link is similar to the one shown in the above named patent and consists of the two cuff-buttons 1 connected 70 together by means of a flexible member, such as a chain.

Each cuff-button consists of a box-member 3 in the bottom 4 of which is centrally disposed a hollow stud 5 provided with a flange 75 6. In the end-walls 7 and 8 of the box-member are provided the apertures 9 and 10 in which is rotatably mounted an axle 11, comprising a shank 12 having at one end the angularly disposed locking-arm 13 and at the 80 other end a diametral slot 14 of suitable length. Surrounding the shank is a coil-spring 15 which is encased in the hollow roller 16. The latter is preferably made from a flat strip of metal bent into a cylinder having a longitudinal slot 17. At one end of said roller is cut at an angle the notch 18.

The coil-spring has at one end the inwardly directed extension 19 which engages the slot 14 of the axle 12, and at the other end of said spring there is formed an outwardly directed hook 20 which is properly shaped to fit within the notch 18.

The flexible connecting member, such as the chain, is made of two parts 2^a and 2^b, each 95 of which is attached to its corresponding button by passing one end of the former through the hollow stud 5 and then hooking the last link thereof to the protruding portion of the hook 20, or by inserting the last 100 but one link flatwise into the longitudinal slot 17, whereby the chain is prevented from pulling out of said slot by the last link. The desired tension in the chain is obtained by turning the axle 12 in the proper direction to wind up the coil-spring 15, and said tension is maintained by pushing the lock-arm 13 into a recess 21 suitably located in the end-wall 7 of the box member. The latter is closed by means of a cover or cap 22, the sides of which 105 fit snugly over the box-member and whereby the lock-arm is held securely in its recess.

The top 23 of said cap may be ornamented in any desired manner to suit the requirements of the trade.

When in normal use, both buttons of a cuff-link must be connected together in order to hold both flaps of a cuff. In the preferred embodiment of my invention I use as releasable connecting means a snap-button of special design comprising the male element 24 and 10 the female element 25, swivelly secured respectively at the free ends of the flexible connecting elements 2^a and 2^b. The ball-portion 26 of the male element fits by snap engagement into the cup-shaped female element 27, the sides of which are preferably slotted, as at 28, to increase the spring action thereof. The rear portions 29 and 30 respectively of the male and female elements are suitably shaped to fit for a certain distance within the flared mouth of each hollow shank, whereby said elements are held in proper position for snapping engagement by the inward pull exerted by the chain-elements 2^a and 2^b. As will be noted from the 20 drawing, the male and female elements 24 and 25 act also as stops for limiting the amount of winding of the flexible elements on their respective drums.

In Figs. 7 and 8 the chain elements 2^a and 30 2^b are releasably connected together by means of a snap-hook 30 and a large link 31 secured respectively at the outer ends of said chains. The shape of said hook and large link is also such as to fit for a considerable 35 distance within the flared mouths of the hollow shanks for reasons stated above.

Another method of releasably connecting together both chain-elements of a cuff-link is shown in Figs. 9 to 12. As illustrated 40 therein, the connector element for the chain 2^a comprises a body-portion 32 and a flattened rear-portion 33 in which an aperture 34 is made for attaching the chain. The body-portion is partly hollowed out, as at 35, 45 and has a central aperture 36. The other connector-element comprises a body 37 having at the front a centrally disposed tubular pin 38 adapted to engage the aperture 36. The body-portion is hollowed out at the rear, as at 39, and is swivelly connected to the chain 2^b by the ball-joint 40 placed in the hollow 39. Secured to the body 37 by means of the screw 41 and engaging the tubular pin 38 is the resilient catch element 42 having at the front a hook 43 and intermediate 55 said hook and rear end 44 the push-button 45. The tubular pin is, of course, provided with suitable apertures to accommodate said hook and push-button. To connect the connector-elements together, the tubular pin is inserted in the aperture 36 and then pushed in until the suitably shaped hook 43 will have entered the hollow 35 and snapped back into normal position to engage the front wall 60 of said hollow. To separate the two buttons

of the cuff-link, sufficient pressure is exerted on the push-button 45 to force the hook inside of the tubular pin 38, the latter being then pulled out of the aperture 36.

To apply a cuff-link of the type shown in 70 Figs. 1 to 6, for instance, the snap connectors 24, 25 are first pulled apart and the flange 6 of each cuff-button is then passed through the corresponding button-hole of the cuff. Then, by properly guiding the cuff-buttons 75 and pressing them against each other, the ball-portion 24 is snapped into the socket-portion 25 whereby the desired connection is established. The frictional engagement between the parts 24 and 25 must be sufficient to overcome the resistance of the tensioned spring 15 when the chain elements 2^a and 2^b are fully unwound, but must be less than the tensile strength of said chains so that 80 when undue stresses are exerted on the cuff-link, said connectors will separate before the chains break, thus automatically preventing any damage to the cuff-link from this source.

As will be understood, as suggested herein, 90 there may be slight changes made in the construction and arrangement of the details of my invention without departing from the field and scope of the same, and I intend to include all such variations, as fall within the scope of the appended claims, in this application in which only a few forms of my invention have been disclosed.

I claim:

1. In a cuff-link, a pair of cuff-buttons; a flexible extensible and retractile member on each button, and means for detachably connecting said flexible members together.
2. In a cuff-link, a pair of cuff-buttons; a flexible extensible and retractile member on each button; means for winding each flexible member into its respective button, and means for detachably connecting said flexible members together.
3. In a cuff-link, a pair of cuff-buttons; a flexible extensible and retractile member on each button; yielding means for winding each flexible member into its respective button, and means for detachably connecting said flexible members together.
4. In a cuff-link, a pair of cuff-buttons; a flexible extensible and retractile member on each button; spring means for winding each flexible member into its respective button, and means for detachably connecting said flexible members together.
5. In a cuff-link, a pair of cuff-buttons; a flexible extensible and retractile member on each button; adjustable spring means for winding each flexible member into its respective button, and means for detachably connecting said flexible members together.
6. In a cuff-link, a pair of cuff-buttons; a flexible extensible and retractile member on each button; adjustable spring means for

winding each flexible member into its respective button, and detachable means for hingedly connecting said flexible members together.

5. 7. In a cuff-link, a pair of cuff-buttons; means for removably securing each button to its corresponding button-hole; a flexible extensible and retractile member on each button; means for winding each flexible member 10 into its respective button, and means for detachably connecting said flexible members together.

8. In a cuff-link, a pair of cuff-buttons; means for removably securing each button

to its coresponding button-hole; a flexible extensible and retractile member on each button; adjustable spring means for winding each flexible member into its respective button, and detachable means for hingedly connecting said flexible members together, said 20 means comprising a female element positioned at the free end of one flexible member and a male element adapted for snap engagement with the female element and positioned at the free end of the other flexible 25 member.

In testimony whereof I affix my signature.
CHARLES W. HEASLEY.
